MOULDING STRIP

Philip Liss, Wilmette, Ill., assignor to Metalcraft Corporation, a corporation of Illinois

Application March 4, 1959, Serial No. 54,837

Term of patent 3½ years

(Cl. D54—2)

Fig. 1 is a plan view of a molding strip embodying my new design;

Fig. 2 is a sectional view of the same, taken on the plane of line 2—2 of Fig. 1; and

Fig. 3 is another sectional view taken on the plane of line 3—3 in Fig. 1.

The design unit is indicated between lines 4—4 in Fig. 1. It is to be understood that this unit is repeated throughout the complete moulding strip.

I claim:

The ornamental design for a moulding strip, substantially as shown and described.
